UNITED STATES PATENT OFFICE.

SAMUEL P. PARMLY, OF CHICAGO, ILLINOIS.

ELECTRIC-ARC LAMP.

SPECIFICATION forming part of Letters Patent No. 540,800, dated June 11, 1895.

Application filed October 26, 1891. Serial No. 409,941. (No model.)

To all whom it may concern:

Be it known that I, SAMUEL P. PARMLY, a citizen of the United States, residing at Chicago, in the county of Cook and State of Illinois, have invented a new and useful Improvement in Arc Lamps, of which the following is a specification.

My invention relates to arc lights and has for its object to provide a double service or 10 long burning arc lamp which shall contain but a single pair of electrodes and shall possess certain advantages with reference to the establishment and maintenance of the arc and with regard to preventing shadows in the light 15 as hereinafter set out. It is illustrated in the accompanying drawings, wherein—

Figure 1 is a side view of the lamp provided with carbons as proposed by me. Fig. 2 is a detail of one form of carbon. Fig. 3 is a detail 20 of another form; Fig. 4, of still another form; Fig. 5, of still another form; Fig. 6, of still another form.

The groups here illustrated are each of them in the general form of an ellipse in cross section or a plate having such a cross-section as would constitute a form having a width substantially one-half its length. The cross-sectional area of these groups is also substantially equal to twice the cross-sectional area of an 30 ordinary round carbon having a diameter equal to the width of the cross-section of my proposed carbon.

A is a case containing the operating mechanism of the lamp. 35 B B are the side bars; C, the upper carbon rod to which the carbon D is attached; E, the lower carbon rod held in the carbon holder F.

G is a carbon substantially elliptical in cross-section. H is a similar carbon with angular edges. 40 J is a carbon right angle in cross-section.

L is a carbon diamond-shaped in cross-section; and M is a carbon elliptical in cross-section. 45

The preferred form of carbon is substantially that shown in Figs. 1, 2 and 6, or in other words, a carbon substantially elliptical in cross-section and having a cross-section whose width is substantially one-half of its 50 length with rounded or flattened ends. The central transverse diameter may be extended

or shortened, as, for example, in the two forms shown in Figs. 2 and 6.

I have found by a long course of experiments that where a carbon formed substantially as suggested is employed in a lamp and placed in opposition to a similar carbon, the tendency is to burn in something like the form indicated in Fig. 1, and also that both carbons or electrodes retain a continuously 55 heated end so that as the arc travels along the opposed edges, which it must do, there is no occasion for it to attack cold material, and hence it is possible to keep a comparatively uniform arc although the same travels back 60 and forth across the edge of the opposed electrode.

A satisfactory arc is obtained without material localization by a construction of electrodes in which the arc is permitted to travel 70 back and forth. The rounded edges of the carbon are not, of course, indispensable, as with the square cornered form shown in Fig. 4 a somewhat similar result is obtained, but it is attended with some irregularity of the 75 arc and also with greater shadow, and hence is not the preferred form. Nor is it indispensable that the carbons should have the precise cross-section indicated, as roughened, grooved or corrugated sides might be used where the 80 grooving or the corrugating is insufficient to prevent the operation of the lamp as hereinbefore described and provided for—that is to say, such change of form would not take a device out of the scope of my invention so long 85 as such changed form of carbon permitted the arc to travel back and forth without material or substantial localization thereof.

Any of these several forms of carbons shown can be used either with a similar carbon above 90 or below or with any other form of carbon above or below. Many other forms of carbons could easily be devised which would be in effect the same as those here illustrated. These several forms, however, when so used keep the 95 arc in motion for the most part and to a very great degree avoid localization of the arc.

I claim—

1. A pair of carbon pencils for an electric arc lamp burning the pencils by holding them 100 in line end to end and having a feed mechanism adapted to adjust the pencils toward one

- another as they are consumed formed each with a total cross sectional area approximately twice that of the round carbons ordinarily employed on a circuit carrying the same current and at least one of them formed as a flattened bar or prism of elliptical cross section with a thickness at the minor axis approximately equal to the diameter of the ordinary round carbon.
10. 2. A pair of carbon pencils for an arc lamp adapted to be presented to one another end to end and to be adjusted toward one another as they are consumed by an arc passing between them each of said pencils having a cross sectional area substantially twice the cross sectional area of the ordinary round carbon and substantially in the form of a flattened bar with thickness and width as one to two and rounded or flattened along its edges.
15. 3. In an electric arc lamp burning its carbons end to end and provided with means for feeding them toward one another as they are consumed by the arc, pencils or electrodes formed each as a flattened bar or prism thick-
20. est at the middle and becoming thinner toward the edges and having a total cross sectional area approximately twice that of the round carbon ordinarily employed on a cir-
25. cuit carrying the same current.
30. 4. A pair of carbon pencils for an electric arc lamp burning two and only two pencils by holding them in line end to end and having a feed mechanism adapted to adjust the pencils toward one another as they are con-
35. sumed, said pencils having each a transverse area double that of the ordinary cylindrical lamp carbons commonly employed on circuits carrying the same number of ampères, and at least one of them formed as a flattened bar or
40. prism of a thickness approximately equal to the diameter of the ordinary cylindrical single lamp carbon and of a width approximately twice its thickness and tapered or thinned from its middle toward its edge.
45. 5. A pair of carbon pencils for an electric arc lamp adapted to be presented to one another end to end and to be adjusted toward one another as they are consumed by an arc passing between them, formed each with an

elliptical or oval figure in cross section the 50 minor diameter of which is approximately that of the round carbon ordinarily employed on a circuit having the same current while its major diameter is sufficient to give the increased mass in cross section required to diminish the rate of consumption to the desired degree.

6. A pair of carbon pencils for an arc lamp adapted to be presented to one another end to end and to be adjusted toward one another 60 as they are consumed by an arc passing between them, formed each as a flattened bar or prism thickest at the middle and becoming thinner toward the edges as and for the purposes described.

7. A pair of carbon pencils for an arc lamp adapted to be presented to one another end to end and to be adjusted toward one another as they are consumed by an arc passing between them, formed each with an elliptical 70 or oval figure in cross section, as and for the purpose described.

8. A pair of carbon pencils for an arc lamp adapted to be presented to one another end to end and to be adjusted toward one another 75 as they are consumed by an arc passing between them, each of said pencils having a cross-sectional area substantially twice the cross-sectional area of the ordinary round carbon and substantially in the form of a 80 flattened bar with thickness and width as one to two.

9. A pair of carbon pencils for an arc lamp adapted to be presented to one another end to end and to be adjusted toward one another 85 as they are consumed by an arc passing between them, each of said pencils having a cross-sectional area substantially twice the cross-sectional area of the ordinary round carbon for the same current, and with a long 90 diameter substantially twice the diameter of an ordinary round carbon for the same current, and shaped so that the arc travels back and forth without material localization.

SAMUEL P. PARMLY.
